(**) Term: **14 Years**

(57) CLAIM

(21) Appl. No.: **29/172,939**

The ornamental design for a cutting insert for chip forming machining, as shown and described.

(22) Filed: **Dec. 20, 2002**

DESCRIPTION

(30) Foreign Application Priority Data

Jun. 28, 2002 (SE) 02-1000

FIG. 1 is a top, front and side perspective view of a cutting insert for chip forming machining showing my new design.

(51) LOC (7) Cl. **15-09**

FIG. 2 is top plan view thereof.

(52) U.S. Cl. **D15/139**

FIG. 3 is a bottom plan view thereof.

(58) Field of Search D15/139; 407/35,

FIG. 4 is a front elevational view thereof.

407/113-118

FIG. 5 is a rear elevational view thereof.

(56) References Cited

FIG. 6 is a right side elevational view thereof; and,

U.S. PATENT DOCUMENTS

FIG. 7 is a left side elevational view thereof.
